UNITED STATES PATENT OFFICE

NEIL SINCLAIR, OF OAKLAND, CALIFORNIA, ASSIGNOR TO RIP VAN WINKLE WALL BED COMPANY, INC., OF OAKLAND, CALIFORNIA, A CORPORATION OF CALIFORNIA

DISAPPEARING BED

Application filed April 4, 1928. Serial No. 267,279.

This invention relates to wall beds of the disappearing type which swing into and out of a closet or cabinet, and has for its objects improved construction and arrangement of the cabinet or closet members, and the operating relation of a plurality of pivotally mounted beds in relation to said members whereby a better concealment of the beds is effected when in the closet, a more compact arrangement with a pair of given size beds is produced, and with a minimum separation of the beds when in let-down position a maximum size free doorway to the closet is had. Also such a doorway between a pair of spaced wall beds which is fitted with a door hinged along both vertical edges of the door in a manner enabling it to swing outward from either vertical edge so as to provide clearance for either bed to swing through the doorway.

In the drawings Fig. 1 is a horizontal cross-section of a cabinet or closet and its doors, with a pair of twin beds concealed in the closet and their outer position dotted, all arranged in accordance with my invention.

Fig. 2 is a front elevation of the showing of Fig. 1.

Fig. 3 is an enlarged vertical section of the cabinet or closet entrance door as seen from the line 3—3 of Fig. 2, Fig. 4 is an enlarged fragmentary section of the door as seen from the line 4—4 of Fig. 2, and Fig. 5 is a plan view of an optional form of one of the door carrying arms.

In the drawings I have illustrated my invention with a pair of twin wall beds of the laterally shifting type, two varieties of which are shown in my copending applications filed respectively under Serial No. 516,939, November 22, 1921 and Serial No. 105,898, May 1, 1926, therefore no exhaustive description of the bed itself will be required here; and it is desired to say that while the maximum benefits of the invention are derived when used with beds which are non-centrally mounted with relation to a door, it has value with other types of beds as well.

In further detail 1 represents the room space defined by a wall 2, and 3 a closet space defined by a wall 4.

A large opening 5 extends through the wall from the room 1 to the closet 3 and is closed by three doors 5, 6 and 7.

Doors 5 and 6 are centrally and vertically pivoted at 8 and 9 so as to rotate in their respective portions of the wall opening, and door 7 is preferably a small door and is hinged at the sides—both sides—in a peculiar way so that it will swing open from either vertical edge in direction of either dotted arc shown in Fig. 1.

Associated with each of the centrally pivoted doors 5 and 6 is a wall bed as at 10 and 11 of the type mentioned and shown as standing upright on end in the closet.

These beds are each wider than the doors with which they are associated and arranged to overlap the wall of the room at their outer vertical edges or rather their vertical edges which are remote from the central door 7 when the beds are in the closet, such overlapping in opposite directions respectively of the two beds being denoted by the letter X.

The beds are pivotally mounted at 12—13 on laterally extending arms 14—15 in turn pivoted concentrically with the door pivots 8—9, and controlled by a link or links as at 16—17 18—19 pivoted at opposite ends to the doors and the beds, or by other means so as to cause the beds to swing in the dotted arcs shown when revolved with their doors so as to bring corner A of bed 10 to A' in the room, and corner B of bed 11 to position B' in the room, and after which the beds may be let down, in the well-known manner, to the positions dotted at C, D.

When the beds are in the room they will be observed to each overlap or extend beyond the same portion of the wall which they did when in the closet and in both positions keep the small door 7 clear, though during their swinging movements they both pass partly through that portion of the wall opening closed by the small door, and in order to so pass through the doorway of the central door it is manifest the door must be gotten out of the way—first at one side to pass bed 10 and then at the other side to pass bed 11.

In order to clear the small doorway for either bed to pass as described, the small door

can be centrally pivoted (if wide enough), but in such a case the available passage way to the closet would only be equal to half the width of the small door and it would accordingly have to be a much wider door so that half of its width would afford an opening large enough for a person to go in and out of the closet.

To avoid the necessity of a wide door which makes the installation take up too much room in modern apartment houses, I have devised the double swinging door 7 which swings freely from either vertical axis 20 or 21 following either dotted arc to open position 7' or 7". Thus the door is opened from one side to pass one of the beds, and from the other side to pass the other bed.

To permit the door 7 to function in the manner described I may mount it in a variety of ways, but the two ways shown in Figs. 1 and 5 are thought sufficiently illustrative.

In Fig. 1 (also Figs. 2, 3 and 4) I provide a pair of horizontally extending arms 22—23 respectively at the top and bottom of the door and close to the rear side of the same.

These arms are provided at one end each with a laterally extending bracket 24—25 each pivoted vertically to the fixed framing on the axis 21. The brackets 24—25 extend over an upper and lower notch in the edge of the door so as to bring the pivotal axis 21 adjacent the outer right hand edge of the door, while the other ends of the arms are joined by a vertical piece 26 (in fact the arms 35 bent to [shape) and to which vertical piece a plurality of hinges 27 are secured, the pins of which form the vertical axis 20. These hinges 27 are secured to the vertical member or run of pipe by bending one leaf around the same as at 27' and bolting thereto as indicated in Fig. 4 while the other leaf is given a right angle bend and screwed both ways to the door 7.

By the arrangement described, the vertical run 26 forms a yoke with and supports the outer ends of the arms and enables them to carry the weight of door 7 on hinges 27 so that it may be opened thereon from the right hand side along the dotted line to position 7', whereas by swinging both the door and yoke on axis 21 the door will open from the left hand side to position 7".

To align the door within the doorway when closed I provide a stop 28 either on the floor or on the framing at the top of the door which limits the inward movement of the door and which may also resiliently clasp an arm so as to form a friction lock for the door, and to keep the right hand edge of the door from rattling or moving out of position I provide a flat metal spring stop 29 secured to the door and so arranged that it also will resiliently clasp the arm or projection therefrom when the door is closed as shown in Fig. 3, or any other form of latch may be used.

In place of the yoke form of arms described, I may employ separate arms at the top and bottom of the door of the form shown at 30 in Fig. 5 and wherein the door 7 and axes 20 and 21 are indicated, but in this case I stabilize the arms by providing each with an extension as at 30' fitted on the end with a stud 31 engaging an arcuate slot in a plate 32 firmly secured to the floor or the framing of the doorway. It being of course evident without further drawings that the stud may be fitted with an anti-friction roller or equivalent if desired.

The construction of door 7 preferably comprises a main panel with two vertical casing pieces A—A secured to and projecting forwardly from the face of the panel. These vertical casings are set inward from the extreme edges of the door so as to produce a quarter inch or three-eighths of an inch step as at B, and to the bottom of the door is secured a base board C extending between the vertical casings A—A, but no casing is provided at the top of the panel.

By the construction described the full realization of a concealed bed is had as the door panel is then painted or papered in conformity with the walls of the room and the two very narrow doors 5 and 6 (shown as glass doors in Fig. 2) give no indication of a wall bed installation.

Since a pair of door knobs on the little door 7 would be objectionable I preferably provide small hanging rings 33 by either of which the door may readily be opened.

I claim:

1. In a closure for a wall bed installation, the combination of a pair of spaced doors mounted in a wall opening to close opposite ends thereof, an intermediate door in said opening positioned between said spaced doors to close the intermediate portion of said wall opening, and means whereby said intermediate door may be swung open from either of its vertical edges thereby cooperating with either of said spaced doors to provide a wider opening than either spaced door would yield when opened alone.

2. A double acting swinging door mounting comprising a door positioned in a doorway, a pair of arms vertically pivoted adjacent one end each above and below the door to the framing of the doorway adjacent one vertical edge of the door, said arms lying substantially horizontal and parallel with said door when closed, and means carried by the other ends of the arms vertically pivoting the door thereto adjacent the opposite vertical edge of the door whereby the door may swing open from either vertical edge.

3. A double acting swinging door mounting comprising a door positioned in a doorway, a pair of arms vertically pivoted adjacent one end each above and below the door to the framing of the doorway adjacent one

vertical edge of the door, said arms lying substantially horizontal and parallel with said door when closed and against the rear face thereof, and means carried by the other ends of the arms vertically pivoting the door thereto adjacent the opposite vertical edge of the door whereby the door may swing open from either vertical edge, and means limiting the inward swinging of the outer ends of said arms when the door is closed.

4. A wall bed installation comprising a pair of spaced doors at opposite ends of a wall opening, an intermediate door in the opening closing the space between said spaced doors, means by which said spaced doors are vertically pivoted to reverse within said opening two wall beds, one positioned adjacent each spaced door and extending along the wall beyond the same in opposite directions away from said intermediate door, means whereby said beds are pivotally mounted each to swing with its adjacent door through the opening to a wall overlapping position as first defined but on the opposite side of said wall, said beds mounted to respectively intersect opposite sides of the space closed by said intermediate door, horizontally extending arms at the top and bottom of said intermediate door, means pivoting the arms at one end to the door adjacent one of its vertical edges, and means pivoting the opposite ends of the arms to a fixed point adjacent the opposite vertical edge of the door whereby the door can swing open from either vertical edge to combine its opening with the opening of either of said spaced doors.

5. A wall bed installation including two wall beds, means whereby the beds are respectively mounted adjacent opposite ends of a wall opening to swing out of a closet through the opening into a room, and a door for each bed spaced at opposite ends of the wall opening each of a width to cover less of said wall opening than required for the bed to pass whereby each bed will intersect the space intermediate the spaced doors in passing through the opening.

6. A wall bed installation including two wall beds, means whereby the beds are respectively mounted adjacent opposite ends of a wall opening to swing out of a closet through the opening into a room, and a door for each bed spaced at opposite ends of the wall opening each of a width to cover less of said wall opening than required for the bed to pass whereby each bed will intersect the space intermediate the spaced doors in passing through the opening in overlapping paths of travel.

7. A wall bed installation including two wall beds, means whereby the beds are respectively mounted adjacent opposite ends of a wall opening to swing out of a closet through the opening into a room, a door for each bed spaced at opposite ends of the wall

opening each of a width to cover less of said wall opening than required for the bed to pass whereby each bed will intersect the space intermediate the spaced doors in passing through the opening, and means mounting 70 said doors for opening with the swinging of their beds and closing their respective ends of the wall opening when the beds are in the closet as well as when in the room.

8. A wall bed installation including two 75 wall beds, means whereby the beds are respectively mounted adjacent opposite ends of a wall opening to swing out of a closet through the opening into a room, a door for each bed spaced at opposite ends of the wall 80 opening each of a width to cover less of said wall opening than required for the bed to pass whereby each bed will intersect the space intermediate the spaced doors in passing through the opening, an intermediate door 85 closing that portion of the wall opening intermediate the spaced doors and means mounting said intermediate door whereby it may be opened from either vertical edge to permit passage of either bed respectively. 90

9. A wall bed installation including two wall beds, means whereby the beds are respectively mounted adjacent opposite ends of a wall opening to swing out of a closet through the opening into a room, a door for 95 each bed spaced at opposite ends of the wall opening each of a width to cover less of said wall opening than required for the bed to pass whereby each bed will intersect the space intermediate the spaced doors in passing 100 through the opening, an intermediate door closing that portion of the wall opening intermediate the spaced doors and means pivoting mounting said intermediate door whereby it may be swung open from either 105 vertical edge to permit passage of either bed respectively.

10. In a structure as specified in claim 4, said arms lying against the rear of the intermediate door when same is closed, and means 110 stopping the arms to hold said door aligned in the wall opening in closed position.
